UNITED STATES PATENT OFFICE.

UBALD HEBERT, OF MANCHESTER, NEW HAMPSHIRE, ASSIGNOR TO DRAPER COMPANY,
OF HOPEDALE, MASSACHUSETTS, A CORPORATION OF MAINE.

FILLING-REPLENISHING MECHANISM FOR LOOMS.

1,185,094.

Specification of Letters Patent. Patented May 30, 1916.

Application filed January 21, 1916. Serial No. 73,450.

To all whom it may concern:

Be it known that I, UBALD HEBERT, a citizen of the United States, residing at Manchester, county of Hillsboro, State of New Hampshire, have invented an Improvement in Filling-Replenishing Mechanism for Looms, of which the following description, in connection with the accompanying drawing, is a specification, like characters on the drawing representing like parts.

This invention relates to automatic filling replenishing mechanism for looms of the Northrop type in which the supply of fresh filling carriers or bobbins is maintained in a rotary battery, feeder or hopper from which upon the call for filling replenishment they are successively transferred to the running shuttle.

More particularly the invention relates to filling replenishing looms of this type in which a definite relation of the filling carrier rotarily of its longitudinal axis with respect to the shuttle walls is requisite, because of the use of filling carriers or bobbins of the general character illustrated in the patents to William Parker Straw No. 908,748, granted December 5, 1908, No. 1,053,673, granted February 18, 1913, and No. 1,092,959 granted April 14, 1914.

The general type of filling mechanism is well known and familiar and reference may be had to the Patent to E. S. Stimpson No. 664,790 granted December 25, 1900 as an illustration of one form thereof. When, however, filling carriers are employed of the character disclosed in the aforesaid patents to Straw, it is desirable that the seats for the butts of the filling carriers located in the periphery of the disk of the hopper instead of being radial as illustrated in the aforesaid patent to Stimpson shall be inclined to the radii of the hopper in order to assist in guiding the filling carriers during transfer to the shuttle on the lay which is beating up as

transfer begins and to insure the proper positioning of the filling carrier in the shuttle to be replenished. In these types of filling replenishing mechanism the bobbin to be transferred is brought by the feeding movement of the hopper into contact with a relatively fixed guiding abutment and during

transfer the bobbin is or should be in contact with this abutment in order to direct it properly into the shuttle. The object of the abutment is thus to maintain the bobbin during transfer in the desired path or line of transfer, but the invention in its broader aspect is not to be limited to the use of such a guiding abutment. When the peripheral seats in the hopper are inclined to the radii of the hopper must have a rotary movement until the bobbin has passed out from the seat in order to maintain the bobbin in guiding contact with the abutment and the hopper must preferably then be locked against further rotary movement until a predetermined reverse movement of the transfer means has taken place sufficient to prevent malposition of the parts such for example as the next succeeding bobbin in the hopper coming into engagement with the transfer means. If this rotary movement of the hopper to maintain the bobbin to be transferred in guiding contact with the abutment during transfer does not take place the bobbin may ride up on the usual pivoted bobbin support located opposite to the abutment or the bobbin may be mispositioned or fail to enter the shuttle, thus preventing replenishment taking place and even causing a smash.

It is the object of the present invention to provide means acting to give the required rotary movement of the hopper to maintain the bobbin being transferred in contact with the abutment until the bobbin passes entirely out from its seat in the hopper and also preferably thereupon to lock the hopper against further rotation until such a reverse movement of the transfer means has taken place as to prevent any improper operation or positioning of the mechanism. These and other objects of the invention will appear more fully from the accompanying description and drawings and will be particularly pointed out in the appended claims.

The drawings illustrate so much of a filling replenishing mechanism of the general type illustrated in the aforesaid patent to Stimpson, but in which the peripheral seats in the hopper are of the inclined type, as is necessary to an understanding of the present invention with preferred forms of mecha-

nism embodying the invention embodied therein.

In the drawings, Figure 1 is an end elevation partially in transverse section of a sufficient portion of the loom necessary to a disclosure of one of the preferred forms of the present invention showing the mechanism in position for transfer; Fig. 2 is a view similar to Fig. 1 showing the parts in the position in which the bobbin is just leaving its seat in the hopper; Fig. 3 is a view similar to Fig. 1 of another form of the invention; Fig. 4 is a view in vertical cross section taken on the line 4—4, Fig. 1.

The general construction of the type of loom illustrated being well known and familiar needs no extended description. It includes the rotatable battery feeder or hopper comprising parallel disks between which the filling carriers such as bobbins are mounted in a circular series. But one of these disks, namely, the disk 1 provided with seats 2 for the butts of the bobbins is illustrated. The hopper is rotatably mounted on the fixed stud 3 rigidly secured to the hopper stand 4 which is itself secured to the loom frame at one side of the loom. A circular flange 5 on the hopper stand surrounds the disk 1 to protect the heads of the bobbins and to retain them in place until they reach substantially their operative position, the flange terminating at the points 6 and 7.

The filling carriers or bobbins 8 illustrated are of the type disclosed in the aforesaid patents to Straw in which the barrel of the bobbin is provided with a transverse slot or opening to coöperate with a feeler whereby absence or exhaustion of the filling in the running shuttle is indicated. This requires that the bobbin when placed in the shuttle shall occupy a definite relation rotarily of its longitudinal axis with respect to the walls of the shuttle. For this purpose the butt of the bobbin is provided with a pair of parallel positioning faces 9 which determine the position of the bobbin in the shuttle. The seats 2 in the disk 1 of the hopper are accordingly formed with parallel walls and of such width as to fit the butts of the bobbins, and thus retain the bobbins in fixed relation in the hopper.

When transfer of the bobbin from the hopper begins the shuttle which is to receive the bobbin is on the lay beneath the hopper and the lay is concluding its beat up toward the left, viewing Fig. 1, and hence in order that the bobbin may more surely enter the bobbin holding or gripping devices in the shuttle in correct position it has been found desirable to position the seats 2 in a direction inclined to the radii of the hopper as indicated in the drawing.

The hopper stand 4 is provided with a relatively fixed abutment 10 against which

the bobbin to be transferred is brought by the rotation of the hopper and during transfer from the hopper the bobbin is guided against this abutment to direct it into the shuttle beneath. The flange 5 terminates at the point 7 a considerable distance from the abutment 10 but is effectively prolonged by the bobbin support 11 pivoted on the hopper stand at 12. This bobbin support serves to retain the bobbins nearest the abutment in their seats in the hopper and yields upon the passage of the bobbin to be transferred to permit its discharge from the hopper.

The mechanism for effecting transfer of the bobbins is illustrated as of a well known type comprising the transfferer 13 pivoted on a horizontal stud 14 carried by the hopper stand 4, and provided with a depending arm 15 through which it is actuated upon the call for filling replenishment. The transfferer is normally elevated through the action of the usual spring 16 and is depressed to effect the transfer movement through the usual connections of the depending arm 15. At its free end the transfferer is provided with a downturned portion 17 to engage the bobbin and discharge it from its seat in the hopper disks.

The hopper is rotated to bring a fresh bobbin into position for transfer by suitable mechanism and in the type illustrated this rotation is secured by a dog 18 pivoted at 19 to the transfferer and provided with a tooth 20 coövering with the teeth of a ratchet wheel 21 integral or moving synchronously with the hopper. Upon the reverse movement of the transfferer the tooth 20 engaging the ratchet wheel 21 rotates the hopper to bring the leading bobbin of the series in the hopper into contact with the abutment 10 and thus into position for transfer.

With the bobbin butt seats 2 inclined it follows that as the bobbin during transfer moves out of its seat it will move away from the abutment 10 and unless the rotation of the hopper is continued to maintain the bobbin in contact with the abutment until after it leaves its seat the bobbin may ride up on the pivoted bobbin support 11 and thus transfer fail to be effected and a smash caused. The hopper is usually free to rotate but it cannot be depended upon to rotate to secure the proper operation of the parts. Consequently this invention provides a means for securing the rotation of the hopper to maintain the bobbin in contact with the abutment 10 during transfer or until after the bobbin leaves its seat.

Filling replenishing mechanism of the type here involved is usually provided with a detent pawl 22. This pawl is provided with a tooth 23 engaging the ratchet wheel 21, and its usual purpose is to prevent reverse rotation of the hopper. The present

invention may, and in the preferred form illustrated does, make use of this detent pawl as one of the elements of the mechanism involved in securing the necessary rotation of the hopper during transfer. For this purpose in the construction illustrated a pawl support 24 is pivoted on a stud 25 projecting from the hopper stand and extends rearwardly past the pivot 14 of the 5 transferrer. The detent pawl 22 is provided with a stud 26 by which it is pivotally mounted midway the length of the pawl support 24. Hence upon the movement of the pawl support 24 the detent pawl 22 is 10 given a bodily movement while it has in addition its usual pivotal movement upon the stud 26. In order to operate the pawl support the transferrer 13, in the construction illustrated, presents rearwardly of its pivot 15 14 an arm 27 extending beneath the rearward end of the pawl support. Preferably also a yielding connection is provided between the arm 27 and the rearward end of the pawl support 24. For this purpose the 20 end of the pawl support is given a cam shaped recess 28 and the arm 27 is provided with a plunger 29 coöoperating with said recess 28, and yieldingly held by the spring 30 in a socket in the arm 27. When now the 25 transferrer 13 in the operation of transfer is moved downwardly into contact with the bobbin to be transferred the arm 27 is elevated and through the yielding plunger 29 and in coöperation with the cam shaped 30 recess 28 swings the pawl support 24 upwardly about its pivot 25, and by a sort of toggle action bodily moves the detent pawl 22 upwardly thus through the medium of the ratchet wheel 21 rotating the hopper and 35 maintaining the bobbin being transferred in contact with the guiding abutment 10, the spring 30 yielding as required to prevent binding of the parts.

In order that the movement of the rotation thus embodied to the hopper may not be excessive or more than required to effect the desired result, a condition which if permitted would bring the next succeeding bobbin in the hopper into contact with the transferrer and thus prevent improper positioning of the parts, it is desirable that the hopper should be locked against further rotation until such a reverse movement of the transferrer has taken place as to prevent any 40 improper operation or positioning of the mechanism. In the construction illustrated in Figs. 1, 2 and 4 this result is secured by means of a brake engaging frictionally the periphery of the hopper. For this purpose 45 the pawl support 24 is provided with a brake arm 31 so positioned that when the bobbin has passed entirely out from its seat in the operation of the transfer this brake arm 31 is brought by the movement of the pawl support into frictional engagement with the

periphery of the hopper disk 1 thus locking it against continued rotation, and during the further downward movement of the transferrer arm the spring 30 yields. This brake arm is held in engagement with the hopper 70 disk until the transferrer arm rises to such a position in its reverse movement that there is no danger of an improper positioning of the parts.

It is also desirable that positive means 75 shall be provided for unlocking the hopper and freeing it to rotation when the necessity for braking action has ended. In the construction illustrated this is secured by providing an upward extension 32 on the transferrer in front of the hub 33 of the pawl support 24 in which the stud 26 is pivoted. This extension 32 is so formed and located that as the transferrer rises in its reverse movement to a position where the braking 80 action may be released it comes in contact with the hub 33, and thus swings the pawl support rearwardly releasing the brake arm 31 from the periphery of the hopper, and thus unlocking the hopper and freeing it to 85 rotation.

The operation of mechanism illustrated in Figs. 1, 2 and 4 will now be apparent. Through the usual upward or reverse movement of the transferrer 13 and the engagement of the tooth 20 of the dog 18 carried thereby with the ratchet wheel 21 the parts have been brought into the position illustrated in Fig. 1 with a bobbin resting against the guiding abutment 10 and upon 90 the tip of the pivoted bobbin support 11 ready for transfer. The detent pawl 22 at this time is held in engagement with the ratchet wheel 21. Upon the call for filling replenishment the arm 15 of the transferrer 100 is pushed rearwardly causing the transferrer to descend and contact with the bobbin therebeneath. This at the same time elevates the arm 27 and causes the pawl support 24 to swing upwardly carrying 105 110 the detent pawl 22 which thereupon as the transferrer continues its downward movement acts to rotate the hopper and maintain the bobbin in contact with the guiding abutment. When the bobbin 115 depressing the bobbin support 11 has entirely freed itself from its seat the friction brake 31 coming into contact with the periphery of the hopper locks it against further rotation and the further descent of the 120 transferrer acting against the spring 30 causes no further movement of the detent pawl. Upon the reverse movement of the transferrer under control of its spring 16 when it has reached a position where there 125 is no danger of the next succeeding bobbin coming into contact with it or the parts being otherwise mispositioned the extension 32 comes against the hub 33 of the pawl support 130 and swings the pawl support 24

rearwardly releasing the brake 31 from the hopper disk and thus enabling the trans-
ferrer on completion of its upward or re-
verse movement acting through the dog 18
again to rotate the hopper to insure the
presence of the next bobbin in position for
transfer. Thus the bobbin being trans-
ferred is carried positively and accurately
downward in contact with the guiding abut-
ment 10 out of its seat and in proper posi-
tion to enter the shuttle beneath on the lay
to be replenished.

The construction illustrated in Fig. 3 is
the same in all respects as that already de-
scribed except that a different means is illus-
trated as an embodiment of the invention
for locking the hopper against undesired
or further rotation until the predetermined
reverse movement of the transerrer has
taken place. In the construction illustrated
in Fig. 3 a means is employed for entering
a recess such as the space between the teeth
of the ratchet wheel 21 and thus positively
locking the hopper against further rotation
at the required time. As an example of
such means the pawl support 24 has pro-
jecting forwardly from its hub 33 a locking
arm 34 so shaped and positioned that when
the transerrer in its downward movement
of transfer has cleared the bobbin from its
seat in the hopper the end of this locking
arm will enter a space between two of the
teeth in the ratchet wheel 21, and thus lock
the hopper against further rotation. Upon
the reverse movement of the transerrer to
the required extent the extension 32 will
as before contacting with the hub 33 swing
the pawl support 24 rearwardly and thus
withdraw the locking arm 34 from engage-
ment with the teeth of the ratchet wheel
21 again leaving the hopper free to rotate.

Having fully described my invention,
what I claim as new and desire to secure
by Letters Patent is:

- 45 1. An automatic weft replenishing loom
comprising a rotary hopper provided with
peripheral bobbin seats inclined to the radii
of the hopper, an abutment to guide the
bobbins in their discharge from the hopper
seats during transfer, means to transfer the
bobbins successively from the hopper to the
running shuttle, and means acting to ro-
tate the hopper and maintain the bobbin
being transferred in contact with the abut-
ment until the bobbin passes from its seat.
- 55 2. An automatic weft replenishing loom
comprising a rotary hopper provided with
peripheral bobbin seats inclined to the radii
of the hopper, an abutment to guide the
bobbins in their discharge from the hopper
seats during transfer, means to transfer the
bobbins successively from the hopper to the
running shuttle, means acting to rotate the
hopper and maintain the bobbin being trans-
ferred in contact with the abutment

until the bobbin passes from its seat, and
means acting thereupon to lock the hopper
against further rotation until a predeter-
mined reverse movement of the transfer
means has taken place.

3. An automatic weft replenishing loom
comprising a rotary hopper provided with
peripheral bobbin seats inclined to the radii
of the hopper, an abutment to guide the
bobbins in their discharge from the hopper
seats during transfer, means to transfer the
bobbins successively from the hopper to the
running shuttle, means acting to rotate the
hopper and maintain the bobbin being trans-
ferred in contact with the abutment until
the bobbin passes from its seat, and a
friction brake acting thereupon to engage
the hopper periphery and lock the hopper
against further rotation until a predeter-
mined reverse movement of the transerrer
means has taken place.

4. An automatic weft replenishing loom
comprising a rotary hopper provided with
peripheral bobbin seats inclined to the radii
of the hopper, an abutment to guide the bob-
bins in their discharge from the hopper
seats during transfer, means to transfer the
bobbins successively from the hopper to the
running shuttle, means acting to rotate the
hopper and maintain the bobbin being trans-
ferred in contact with the abutment until
the bobbin passes from its seat, and a friction
brake controlled by said last mentioned
means acting thereupon to engage the hop-
per periphery and lock the hopper against
further rotation until a predetermined re-
verse movement of the transerrer means has
taken place.

5. An automatic weft replenishing loom
comprising a rotary hopper provided with
peripheral bobbin seats inclined to the radii
of the hopper, an abutment to guide the bob-
bins in their discharge from the hopper
seats during transfer, means to transfer the
bobbins successively from the hopper to the
running shuttle, means acting to rotate the
hopper and maintain the bobbin being trans-
ferred in contact with the abutment until
the bobbin passes from its seat, and locking
means controlled by said last mentioned
means acting thereupon to lock the hopper
against further rotation until a predeter-
mined reverse movement of the transerrer
means has taken place.

6. An automatic weft replenishing loom
comprising a rotary hopper provided with
peripheral bobbin seats inclined to the radii
of the hopper, means to transfer the bobbins
successively from the hopper to the running
shuttle, and means acting to rotate the hop-
per to maintain the bobbin being transferred
in the path of transfer until the bobbin
passes from its seat.

7. An automatic weft replenishing loom
comprising a rotary hopper provided with

peripheral bobbin seats inclined to the radii of the hopper, means to transfer the bobbins successively from the hopper to the running shuttle, means acting to rotate the hopper to maintain the bobbin being transferred in the path of transfer until the bobbin passes from its seat, and means acting thereupon to lock the hopper against further rotation until a predetermined reverse movement of the transfer means has taken place.

8. An automatic weft replenishing loom comprising a rotary hopper provided with peripheral bobbin seats inclined to the radii of the hopper, means to transfer the bobbins successively from the hopper to the running shuttle, means acting to rotate the hopper to maintain the bobbin being transferred in the path of transfer until the bobbin passes from its seat, and a friction brake acting thereupon to engage the hopper peripherally and lock the hopper against further rotation until a predetermined reverse movement of the transfer means has taken place.

9. An automatic weft replenishing loom comprising a rotary hopper provided with peripheral bobbin seats inclined to the radii of the hopper, means to transfer the bobbins successively from the hopper to the running shuttle, means acting to rotate the hopper to maintain the bobbin being transferred in the path of transfer until the bobbin passes from its seat, and a friction brake controlled by said last mentioned means acting thereupon to engage the hopper periphery and lock the hopper against further rotation until a predetermined reverse movement of the transfer means has taken place.

10. An automatic weft replenishing loom comprising a rotary hopper provided with peripheral bobbin seats inclined to the radii of the hopper, means to transfer the bobbins successively from the hopper to the running shuttle, means acting to rotate the hopper to maintain the bobbin being transferred in the path of transfer until the bobbin passes from its seat, and locking means controlled by said last mentioned means acting thereupon to lock the hopper against further rotation until a predetermined reverse movement of the transfer means has taken place.

11. An automatic weft replenishing loom comprising a hopper stand, a hopper rotarily mounted therein and provided with peripheral bobbin seats inclined to the radii of the hopper, a ratchet wheel connected to and rotating with the hopper, a transferrer pivotally mounted on the stand, a pawl support pivotally mounted on the stand, a detent pawl pivotally mounted on the pawl support and coöoperating with the ratchet wheel, a yielding connection between the transferrer and pawl support whereby upon transfer movement of the transferrer the pawl support is rocked to give a bodily movement to the detent pawl and thereby upon transfer movement of the transferrer the hopper to maintain the bobbin being transferred in its required path of transfer until the bobbin passes from its seat.

and therethrough to rotate the hopper to maintain the bobbin during transfer in its required path of transfer.

12. An automatic weft replenishing loom comprising a hopper stand, a hopper rotarily mounted therein and provided with peripheral bobbin seats inclined to the radii of the hopper, a ratchet wheel connected to and rotating with the hopper, a transferrer pivotally mounted on the stand, a pawl support pivotally mounted on the stand, a detent pawl pivotally mounted on the pawl support and coöoperating with the ratchet wheel, a yielding connection between the transferrer and pawl support whereby upon transfer movement of the transferrer the pawl support is rocked to give a bodily movement to the detent pawl and therethrough to rotate the hopper to maintain the bobbin during transfer in its required path of transfer, and means operated by the pawl support to lock the hopper against further rotation until a predetermined reverse movement of the transferrer has taken place.

13. An automatic weft replenishing loom comprising a hopper stand, a hopper rotarily mounted therein and provided with peripheral bobbin seats inclined to the radii of the hopper, a ratchet wheel connected to and rotating with the hopper, a transferrer pivotally mounted on the stand, a pawl support pivotally mounted on the stand, a detent pawl pivotally mounted on the pawl support and coöoperating with the ratchet wheel, a yielding connection between the transferrer and pawl support whereby upon transfer movement of the transferrer the pawl support is rocked to give a bodily movement to the detent pawl and therethrough to rotate the hopper to maintain the bobbin during transfer in its required path of transfer, and a friction brake carried by the pawl support and thereupon brought into engagement with the hopper periphery to lock the hopper against further rotation until a predetermined reverse movement of the transferrer has taken place.

14. An automatic weft replenishing loom comprising a rotary hopper provided with peripheral bobbin seats inclined to the radii of the hopper, means to transfer the bobbins successively from the hopper to the running shuttle, and means yieldingly operated by said transfer means acting to rotate the hopper to maintain the bobbin being transferred in its required path of transfer until the bobbin passes from its seat.

15. An automatic weft replenishing loom comprising a rotary hopper provided with peripheral bobbin seats inclined to the radii of the hopper, a ratchet wheel rotatable with the hopper, a movably mounted transferrer, and means for actuating it to cause

it to transfer the bobbins successively from the hopper to the running shuttle, a movably mounted detent pawl engaging said ratchet wheel, and means acting upon transfer to give a yielding bodily movement to said detent pawl to cause it acting upon the ratchet wheel to rotate the hopper to maintain the bobbin being transferred in its required path of transfer until the bobbin 10 passes from its seat.

16. An automatic weft replenishing loom comprising a hopper stand, a hopper rotarily mounted therein and provided with peripheral bobbin seats inclined to the radii of the hopper, a ratchet wheel connected to and rotating with the hopper, a transferrer pivotally mounted on the stand, a pawl support pivotally mounted on the stand, a detent pawl pivotally mounted on the pawl support and coöperating with the ratchet wheel, a yielding connection between the transferrer and pawl support whereby upon transfer movement of the transferrer the pawl support is rocked to give a bodily movement 20 to the detent pawl and therethrough to rotate the hopper to maintain the bobbin during transfer in its required path of transfer, means operated by the pawl support to lock the hopper against further rotation, and 30 means operated by the transferrer to unlock the hopper when a predetermined reverse movement of the transferrer has taken place.

17. An automatic weft replenishing loom comprising a hopper stand, a hopper rotarily mounted therein and provided with peripheral bobbin seats inclined to the radii of the hopper, a ratchet wheel connected to and rotating with the hopper, a transferrer 40 pivotally mounted on the stand, a pawl support pivotally mounted on the stand, a detent pawl pivotally mounted on the pawl support and coöperating with the ratchet wheel, a yielding connection between the transferrer and pawl support whereby upon transfer movement of the transferrer the pawl support is rocked to give a bodily movement to the detent pawl and therethrough to rotate the hopper to maintain the 50 bobbin during transfer in its required path of transfer, a friction brake carried by the pawl support and thereupon brought into engagement with the hopper periphery to lock the hopper against further rotation, and 55 an extension of the transferrer acting to contact with the pawl support when a predetermined reverse movement of the transferrer has taken place and therethrough release the friction brake.

18. An automatic weft replenishing loom comprising a rotary hopper provided with peripheral bobbin seats inclined to the radii of the hopper, an abutment to guide the bobbins in their discharge from the hopper

seats during transfer, means to transfer the 65 bobbins successively from the hopper to the running shuttle, means acting to rotate the hopper and maintain the bobbin being transferred in contact with the abutment until the bobbin passes from its seat, means acting 70 thereupon to lock the hopper against further rotation, and means acting to unlock the hopper when a predetermined reverse movement of the transfer means has taken place.

19. An automatic weft replenishing loom 75 comprising a rotary hopper provided with peripheral bobbin seats inclined to the radii of the hopper, an abutment to guide the bobbins in their discharge from the hopper seats during transfer, means to transfer the 80 bobbins successively from the hopper to the running shuttle, means acting to rotate the hopper and maintain the bobbin being transferred in contact with the abutment until the bobbin passes from its seat, a friction 85 brake acting thereupon to engage the hopper periphery and lock the hopper against further rotation, and means acting to release the friction brake when a predetermined reverse movement of the transferrer means has 90 taken place.

20. An automatic weft replenishing loom comprising a rotary hopper provided with peripheral bobbin seats inclined to the radii of the hopper, an abutment to guide the bobbins in their discharge from the hopper seats during transfer, means to transfer the 95 bobbins successively from the hopper to the running shuttle, means acting to rotate the hopper and maintain the bobbin being transferred in contact with the abutment until the bobbin passes from its seat, a friction 100 brake controlled by said last mentioned means acting thereupon to engage the hopper periphery and lock the hopper against 105 further rotation, and means controlled by the bobbin transferring means acting to release the friction brake when a predetermined reverse movement of the transfer means has taken place.

21. An automatic weft replenishing loom comprising a rotary hopper provided with peripheral bobbin seats inclined to the radii of the hopper, means to transfer the bobbins successively from the hopper to the running 115 shuttle, means acting to rotate the hopper to maintain the bobbin being transferred in the path of transfer until the bobbin passes from its seat, means acting thereupon to lock the hopper against further rotation, 120 and means acting to unlock the hopper when a predetermined reverse movement of the transfer means has taken place.

22. An automatic weft replenishing loom 125 comprising a rotary hopper provided with peripheral bobbin seats inclined to the radii of the hopper, means to transfer the bobbins successively from the hopper to the running

shuttle, means acting to rotate the hopper to maintain the bobbin being transferred in the path of transfer until the bobbin passes from its seat, a friction brake controlled by 5 said last mentioned means acting thereupon to engage the hopper periphery and lock the hopper against further rotation, and means

controlled by the bobbin transferring means acting to unlock the hopper when a predetermined reverse movement of the transfer 10 means has taken place.

In testimony whereof, I have signed my name to this specification.

UBALD HEBERT.
